FIRE ALARM SIGNALING SYSTEM

Paul P. Horni, Newark, N. J.

Application October 20, 1937, Serial No. 169,952

5 Claims. (Cl. 177—367)

Signaling systems such as those employed on fire alarm and like installations, must necessarily have a great degree of reliability of operation to insure public safety and minimize the loss due to destruction of property by fire.

Faulty conditions which frequently arise in a fire alarm signaling system, must be handled so that they are quickly corrected without materially affecting the operation of the system or appreciably delaying rapid and certain notification at fire headquarters of an alarm box which has been actuated.

Some of the signaling systems which are now in commercial use, not only utilize the normally closed signaling loop energized by direct current, but also employ an alternating current superimposed on the loop for signaling box location numbers and/or supervising the loop continuity.

To use a superimposed alternating current on a direct current energized signaling system, or vice versa, it is necessary to use coupling means, for example, condensers. While various signaling systems in the signaling art show the use of a single condenser to couple the alternating current energy source with the direct current energized signaling loop to afford proper operation under a given set of circumstances, it is shown to be very old in the art to use two condensers having one side of each condenser connected to conductors of opposite polarity and to have the opposite sides of the condenser suitably connected so that a point intermediate the two condensers may be connected to a third conductor, such as a ground. An example of this type of coupling is shown in the patent to Alfred Charles Brown, Patent #1,181,427, issued May 2, 1916. The Brown patent also shows the use of a single condenser.

Specifically, reference may be had, for a more comprehensive understanding of the present invention, to Figures 4 and 3, respectively, of the above-mentioned Brown patent, for a showing of the use of two condensers and a single condenser.

The present invention has for an object, the use of alternating current superimposed on a signaling system energized by direct current, and having a condenser coupling connecting one side of an alternating current source through a rectifier to a condenser, and from the opposite side of the condenser to the ground, which condenser may be cut out of the circuit to connect the one side of the rectifier directly to the ground in the event there is a failure of the alternating current energy source which is impressed upon the system, the opposite side of the secondary of the

energy source, which is shown in Figure 1, being connected to the loop.

The further object of the invention is to provide an alternating current source to be used in conjunction with a direct current signaling loop, wherein one side of the alternating current energy source is impressed on the signaling system at a mid-point of the battery to enable the signaling system to have substantially equal impressed voltages on either side of the loop in the event of an open circuit in said loop.

The further object is to utilize coupling means to shunt manifestation devices so that the alternating current which is used in the system may have an easy path without encountering the inductive effect of the coils of certain devices in the system.

Other and further objects may become apparent to those skilled in the art, after a perusal of the present invention.

Figure 1 is a schematic wiring diagram of the present invention essentially as a unit.

Figure 2 indicates an open condition in the loop to show the various signaling paths primarily for the direct current.

Figures 3 and 4 are components of the diagram shown in Figure 2, and set forth the actual current paths of the components derived from the circuit shown in Figure 2.

Referring particularly to Figure 1, we have a signaling loop 1, such as several boxes or initiating stations connected therein, which boxes are indicated as 2, 3, 4, 5, 6, and 7. The box 7 is similar to the box shown in Patent No. 1,528,596, which is of the type that has signaling contact sets 8 and 9, which are serially connected into the loop 1 for the purpose of interrupting the signaling current. The contact 10 is associated with an armature 11 which connects a point intermediate the two contact sets 8 and 9 to the ground or common return 12. The ground switch is of the type that closes before or substantially simultaneously with the first opening of the contact sets 8 and 9, and ultimately opens before or substantially simultaneously with the final closure of the contact sets 8 and 9. The box 6 is merely representative of the conventional non-interfering transmitter which may be of the succession type and is used in the present instance to show the operation of this box in conjunction with the present invention. An example of this type of transmitter is presented in the copending application, Serial No. 85,311, filed June 15, 1936. Box 7 is merely representative of what is commonly referred to by those skilled in the art.

as a "bulldog" box while box 6 is merely representative of a non-interfering box. Both boxes 1 and 6 are of the type which, under certain conditions, will cause a signal to be transmitted over 5 an auxiliary circuit.

Box 6 has a contact set 13, which is in fact a conventional box shunt, and connects terminals 14 and 15 together to complete the loop circuit, when the transmitter 6 is not in operation. Terminal 14 is connected to a contact set 16, which is in turn connected to one side of a non-interference magnet 18, the opposite side of said magnet 18 being connected to one side of a non-interference magnet 19, the opposite side of which 15 magnet 19 is connected to a contact set 17, which has one side thereof connected to the terminal 15. It will, therefore, be seen that when the contact set 13 is opened, a circuit may be traced from terminal 14 through the contact 16, non-interference magnet 18, non-interference magnet 19, contact set 17, to the terminal 15, which shows that the non-interference magnets are in series with the loop and that the revolving of the code wheel 20 by any conventional motor will 20 permit the code wheel follower 21 to drop down into the indentures on the code wheel and thereby cause opening and closing the contact sets 16 and 17 in conformance with the indentures on the code wheel. The code wheel 21' in the 25 box 7, likewise will, when caused to revolve by the operation of the box motor, permit the contact sets 8 and 9 to open and close in response to the irregular peripheral surface of the code wheel 21'.

Under normal conditions, it will be seen that a combined voltage of the battery units 22 and 23 will be impressed upon the signaling loop at terminals 24 and 25'. Therefore, when the loop is closed, the current will flow from the positive side of battery 22 to the terminal 24, over conductor 25, through register 26, over the conductor 27, through the boxes 2, 3, 6, 7, 5, and 4, through a conductor 28, through a manifestation means 29, a conductor 30, back to the negative side of the battery 23, the positive side of said battery 23 being connected to the negative side of battery 22.

It will, therefore, be seen that the voltage impressed upon the system under the closed loop 50 will be the combined voltages of the batteries 22 and 23. The manifestation device 29, which has just been referred to, is in series with the loop, and may have its armature 31 connected to either contacts 32 or 33, which may be used as a control 55 circuit for other devices such as line relays in the event the devices are electrically connected with other signaling loops through repeaters or may be connected to operate a manifestation device of the type shown as 26 in Figure 4, which 60 is shown as a register of the tape puncturing type, which is responsive to signaling impulses initiated in a transmitter. Condensers 34 and 35 are connected respectively across the register 26 and the magnet shown as 29. As has been previously 65 explained, the purpose of these condensers is to permit the passage of alternating current through said devices without encountering the inductive effect of the devices 26 and 29. The primary of an alternating current transformer 36 is connected to an alternating current source, which 70 primary feeds the secondary 37. A rectifier 45 is connected in series with the secondary, and a condenser is connected to ground therefrom, so that a circuit may be traced from the mid-point 75 38 between two battery units, over a conductor

39, to a terminal 40, over the secondary of the transformer 37, to a terminal 53, terminal 42, to the rectifier. The opposite terminal 43 of the rectifier 45 is connected to one side of a blocking condenser 44, the opposite side of said condenser 5 being connected to a ground 12.

The alternating current impressed upon the rectifier 45 will have two leads which connect from terminal 46 to a conductor 47, to one side of a register 48, which is responsive to direct current, the opposite side of said register being connected to a conductor 49, then to the terminal 50 of the rectifier 45.

It will, therefore, be seen that any actuation of the signaling contacts 16 and 17 in box 6, 15 or signaling contacts 8 and 9 in box 7, will actuate the register 26 and thereby communicate to headquarters any impulses originated in the initiating stations. These impulses will also be impressed upon the magnet 29 for the purpose 20 of operating a manifestation means such as 58, in the event same were connected to terminals 31 and 32 of the manifestation device 29, as is shown in Figure 4.

The transmitter 7, in Figure 1, has a ground 25 connection 12, which is connected to the box during the operation of said transmitter, while the box 6 is of the type which utilizes a ground connection and is connected to said ground when contact 51 is engaged by the moving member 52, 30 operable by any conventional mechanism. In this particular type of transmitter, the contact set 13 which is in fact a box shunt, is opened before the signaling contacts start to operate. In the event the loop is closed and the signal operates normally, the contact set 51—52 will not be closed. However, in the event of an abnormal opening in the line, the mechanism, which may be of any conventional type, will cause the contact set 51—52 to close for the purpose of 40 signaling over the common return or ground conductor 12.

However, for this to occur, it will be necessary to provide a signaling path to the ground at the central office, which path in the present invention is not provided unless there is a failure of the alternating current source, the reason for this being that it is not necessary in the given case to signal with direct current over the ground as long as there is alternating current provided 50 for the system.

With the type 6 box and the loop normal, only the direct current signal would be received on the register 26 and the manifestation device 29 for the register 58, if same was connected as 55 shown. However, in the type of box such as 7, both the registers 26 and the manifestation means 29, and also the register 48 would be operated by each signaling impulse.

In the event of a shunted box, it will be seen 60 that in both cases of the types of transmitters indicated, the direct current signal would not be able to get through. However, regarding the alternating current signal, it will be seen that in both the 6 and 7 types of transmitters, the alternating current signal would be able to get through to headquarters.

In Figure 1 it will be seen that a relay 54, responsive only to alternating current, is shown by the conventional symbol, and is in series with 70 a condenser C. The alternating current relay 54, and the condenser which are in series, are connected across the terminals 40 and 53 of the winding 37. This relay 54 is a supervisory relay for the alternating current secondary and said 75

relay 54 is energized at all times when the normal alternating current is impressed on the system. In the event of failure of the alternating current source, the armature 55 of the relay 54 will drop back to engage contact 56. It will, therefore, be seen that the condenser 44 which was connected from terminal 43 of the rectifier to the ground 12, will now be short-circuited by the contact set 55-56 to connect the terminal 43 directly to the ground 12, thereby providing a path for the direct current, from the battery of the central office equipment to the ground 12.

For the purpose of explanation, Figure 2 is hereby shown as being more clearly representative of the direct current circuit which would result, in the event the alternating current source fails and the relay 54 permitted its contact set 55-56 to connect terminal 43 directly to the ground 12, over the conductor 57. At X on Figure 2, between boxes 3 and 5, we see the two ends of the loop L and L' which represents the open ends of the signaling conductor, which open in the loop interrupts the continuity of the normally closed signaling loop. With the above-mentioned condition and the failure of the alternating current power, the manifestation devices 28 and 29, respectively, would be operated in response to the initiating stations such as 2, 3, 4, and 5, over a ground connection. While these boxes which are shown in Figure 2 are merely symbolic of an initiating station, it is to be understood that they may be of any suitable type and are not limited to a particular type of transmitter.

Figures 3 and 4 are representative of the circuit components of Figure 2, and show the opposite sides of a loop with their independent energy sources as being independent signaling circuits, which they are in fact, even though certain of the conductors such as the ground and rectifier and its associated parts provide a common path for the current flow. It will be seen that in both Figures 3 and 4, that the register 48 and part of the rectifier and the secondary 37, are each common conductors for both sides of the loop. In Figure 3 it will be noted that when a box is pulled such as that shown as Fig. 6, the transmitter will eventually connect to the ground so that at least one of its signaling contacts will be able to interrupt the current flow and impulse the circuit for the purpose of signaling its station identifying number. When the circuit is closed through the ground switch such as contact set 51-52 of 6, a circuit may be traced from the positive side of battery 22, over conductor 25, through register 26, through conductor 27, through box 2, box 3, and assuming box 3 is the station actuated, from the ground contacts of the last-mentioned box to the common return or ground 12. The circuit may then be traced from the ground 12 which is connected to the transmitter 3, to the ground 12 which is connected to the terminal 43 of the rectifier 45, over the Z side of the rectifier 45, through conductor 47, through the register 48, over the conductor 49 to terminal 50, through the winding 37 of the transformer secondary 37, to terminal 38, back to the negative side of the battery 22. Assuming that box 5 is pulled on the circuit shown in Fig. 4, a current path may be traced from the positive side of the battery 23, to terminal 38, through the transformer secondary 37 through the Y side of the rectifier 45, through conductor 47, register 48, conductor 49, through the Y' side of the rectifier, to terminal 43, back to ground 12,

through the ground to the connection in box 5, (such as contacts 51 and 52 in Figure 1), which connects the ground to the loop, over the conductor 28 to the manifestation means 29, through conductor 30 and back to the negative side of battery 23. For the purpose of explanation, a register is shown as 58, and is connected to the contacts of the manifestation means 29 so that at each impulse of the circuit, a register will be operated.

A circuit may be traced from terminal 31, through contact 32, over the conductor 59 to battery 60, conductor 61, through the register 58 and back to the terminal 31. In this case, the register will be operated at each impulse and the station identifying number will be recorded thereon in response to the impulses of the signaling transmitter. While the register 58 has been shown connected to operate in response to the component of Figure 2 shown as Figure 4, it is clear that the register 48 may operate in response to any box on the loop under normal conditions since this register may have the characteristics which will permit it to respond to half of the full voltage impressed on the closed loop. The register in itself, under normal conditions, responds to direct current since the alternating current which is the source of energy, is rectified to supply direct current for the register 48. It is to be noted that the direction of current flow through the register 48 is the same in both components shown in Figures 3 and 4 of Figure 2.

From the foregoing discussion, it is pointed out that the alternating current source may fail and that in this event the coupling means would be disconnected from the circuit by a contact set such as 55-56 so that the loop may be metallically connected to ground.

While specific details of the system have been herein shown and described, the invention is not confined thereto as changes and alterations may be and may become apparent to those skilled in the art without departing from the spirit thereof as defined by the appended claims.

Having thus described the invention, what I claim as new and desire to secure by Letters Patent of the United States, is—

1. A signaling system comprising a normally closed signal loop energized by direct current, a common conductor, transmitters in the loop having means for opening and closing the signal loop and for connecting both ends of the loop at the transmitter to the common conductor, a winding connected across said signal loop and said common conductor to provide an alternating electromotive force therebetween, a coupling means electrically connected intermediate one side of said winding and said common conductor to prevent the passage of direct current, electro-magnetic means connected across said winding, and a circuit closure means responsive to deenergization of said electromagnetic means to shunt said coupling means to permit the passage of direct current.

2. A fire alarm signaling system comprising a signal loop energized from a direct current source having an electrical mid-point terminal said loop including signal initiating stations capable of signal transmission over said loop, and said loop and a common return conductor, and a common return therefor, a condenser, a rectifier having two input terminals and two output terminals, an alternating electromotive force source having two terminals one of said terminals being connected to one of said rectifier input terminals, the other of said alternating electromotive force source ter-

minals being connected to the electrical mid-point terminal of the direct current source, the other of said rectifier input terminals being connected to said common return conductor through said condenser, a signal receiver connected across said output terminals of said rectifier, and electromagnetic means shunting said alternating electromotive force source and responsive thereto capable of short circuiting said condenser upon failure of the alternating electromotive force source, to the end that in the event the alternating current source should fail and the loop continuity should become disrupted any signal initiating stations operated on either side of the direct current source would actuate the signal receiver connected across the rectifier output terminals.

3. A fire alarm signaling system comprising a normally closed signal circuit having signal transmitters therein for opening and closing the signal current and for connecting both ends of said signal circuit to a common return path, and a source of direct current energy therefor, a common return path, a transformer having a secondary winding to impress an alternating electromotive force between said normally closed signal circuit and said common return path, a blocking condenser serially connected intermediate one side of said secondary and the common return path, means connected across said secondary and energized thereby, and a normally open contact set responsive to said last mentioned means having one contact connected to the common return path and the other contact connected to a point intermediate said secondary and said blocking condenser, whereby in the event the transformer secondary should become deenergized the contact set would close and short circuit said blocking condenser.

4. A fire alarm signaling system comprising a direct current energized loop having signal transmitters connected therein for opening and clos-

ing the loop and for connecting both sides of said loop to a common conductor, a common conductor, an energized transformer winding to impress an alternating electromotive force between said loop and said common conductor, a coupling means to prevent the passage therethrough of direct current connected intermediate one side of said transformer winding and the common conductor, means normally energized connected across said transformer winding, and means responsive to said last mentioned means to connect the common conductor directly to a point intermediate said transformer winding and said coupling means in the event there would be an absence of the alternating electromotive force in said transformer winding.

5. A signaling system comprising a normally closed signal loop energized by direct current and including signal initiating stations capable of signal transmission over said loop, and said loop and a common return conductor, and of connecting said signal initiating stations to a common return conductor, a common return conductor, a rectifier having input and output terminals, a condenser, an alternating electromotive force source serially connected to the input terminals of said rectifier, said electromotive force being impressed between the loop and the common return conductor through said rectifier and said condenser, a signal receiver connected to the output terminals of said rectifier for receiving signal impulses from said initiating stations, and electromagnetic responsive means connected across the electromotive force source to shunt the condenser and provide a signal conducting by-pass from the loop to the common return conductor in the event the alternating electromotive force should fail to maintain the electromagnetic responsive means in an operative condition.

PAUL P. HORN. 40
